UNITED STATES PATENT OFFICE

THOMAS E. BUCKNER, OF PLASKA, TEXAS

CONVEYER BELT

Application filed March 11, 1929. Serial No. 346,059.

The present invention appertains to improvements in conveyer belts and more particularly to a novel distributor belt especially adapted for use in cotton gin machinery.

The belt in this capacity conveys the cotton to the distributor boxes for uniform distribution to the several gin saws. In this type of belt structure a plurality of transversely spaced prongs are attached to the belt at longitudinally spaced intervals. The prongs are individually connected to the belt in the conventional structures, so it is the primary object of this invention to provide a belt structure wherein the prongs of the transversely spaced clusters are of unitary construction and secured to the belt in such a manner as to relieve considerable strain which is now exerted on the belt material due to the inadequate means whereby the prongs are attached to the belt.

Other objects of the invention are to prevent the prongs from becoming disengaged from the belting, permitting use of lighter fabric in the belting, increasing the carrying capacity, greater strength and durability, permitting less tension on belting in use, and permitting ready repair and replacement of worn parts.

These and other objects of the invention will become more apparent to the reader after considering the invention as described and claimed hereinafter.

In the drawing:

Figure 1 represents the fragmentary side elevation of the improved belt.

Figure 2 is a perspective view of one of the pronged units.

Figure 3 is a perspective view of one of the brace members for the pronged units.

In the drawings wherein like numerals designate like parts, the belting consists of a multiplicity of elongated sections 3, each section preferably being of multiply con-

struction, as is clearly shown in Figure 1, the adjacent ends of the sections are bent laterally and disposed in abutting relation. To one outer side of the abutting ends of one pair of sections is engaged one of the novel units generally referred to by numeral 4, while against the opposite outside faces of the abutting ends the bracing unit generally referred to by numeral 5 is engaged, and adapted for bracing engagement with the pronged unit 4.

The pronged unit 4 consists in construction of an elongated strip 6 provided with a plurality of longitudinally spaced openings 7 through which fastening means 8 may be disposed in connecting the units 4 and 5, and the abutting ends of the sections together. The strip 6 is provided with a suitable number of right angularly disposed prongs 9 disposed in substantial parallelism with respect to each other. The prong members are adapted to project outwardly from the belt sections for engaging and pushing a batch of cotton toward the gin machinery.

The bracing unit 5 consists in construction of an elongated strip 10 provided with a plurality of longitudinally spaced openings 11. The strip has a plurality of spring fingers 12 projecting laterally therefrom and these fingers are each provided at its free end with a laterally disposed lug 13 for engagement with a corresponding prong 9 of the unit 4. Thus the pronged unit is clearly braced by means of the unit 5, while the strips 6 and 10 of the respective units 4 and 5 reinforce the laterally disposed and abutting ends of the belt section.

Obviously the units as well as the belting may be of any size desirable and of any material, and numerous changes in the shape thereof may be resorted to without departing from the spirit and scope of the invention as claimed hereinafter.

Having thus described the invention, what

I claim as new and desire to secure by Letters Patent is:-

A follower for conveyer belts, wherein the belt is provided with a transversely extending rib; a fork-shaped follower unit adapted to have its back edge portion disposed against one side of the rib, a brace unit comprising a plate for disposition against the opposite side of the rib, a plurality of spring fingers extending laterally from said plate, the free ends of said fingers being offset for tensional engagement against the prongs of the said fork.

In testimony whereof I affix my signature.

15 THOMAS E. BUCKNER.
